UNITED STATES PATENT OFFICE.

GUSTAVE GIN, OF PARIS, FRANCE.

CONSTRUCTION OF INDUCTION ELECTRIC FURNACES.

No. 875,961.

Specification of Letters Patent.

Patented Jan. 7, 1908.

Application filed May 8, 1906. Serial No. 315,028.

To all whom it may concern:

Be it known that I, GUSTAVE GIN, a citizen of the French Republic, and resident of 43 Rue de Lévis, Paris, France, have invented a certain new Construction of Induction Electric Furnaces, of which the following is a specification.

In induction electric furnaces of the types heretofore employed it is difficult to obtain a uniform distribution of heat and uniform reactions in different parts of the furnace on account of the small calorific conductivity and slow diffusibility of molten substances. A much more satisfactory effect may be obtained by the employment of means for producing a continuous circulation of the molten materials in the furnace, thereby causing a thorough mixing of all their particles and constantly renewing their contact surfaces with the reactive agents employed. This circulation may be obtained by forming the channel crucible of a succession of open channels or receptacles, the bottom of each being longitudinally sloping, and by connecting these channels or receptacles by means of laterally closed conduits connecting the deep end of each channel with the shallow portion of the adjacent channel.

The Joule effect which varies in an inverse ratio with the section of the molten mass is less intense in the deep portion of the open channels. As the two liquid masses which communicate through closed conduits have different densities on account of the difference in temperatures, an upward movement of the liquid molecules in the closed channels is produced. This displacement is still further reinforced by the heating in the conduit itself. From these partial displacements a general and continuous circulation results throughout the whole molten mass filling the channels.

In the drawing, in which like reference numerals indicate corresponding parts, Figures 1 and 2 are respectively vertical and horizontal sectional views of a crucible constructed in accordance with my invention, Fig. 1 being a section on line *a*—*b* indicated in Fig. 2. Figs. 3 and 4 are horizontal sectional views of modified forms of furnaces embodying my invention, the channels being curved.

In the drawings, *A* designates a furnace hearth of refractory, nonconductive material, provided with a plurality of open channels as 1, 2, 3, etc., indicated in the various

figures of the drawings. These channels, which may be either straight or curved, as shown, are provided with longitudinally sloping bottoms *B*. A series of inclined, laterally closed conduits or flues *C* connect each of the open channels with the adjacent ones, the shallow end of each channel being connected with the deep end of the adjacent channel as clearly indicated in Fig. 1.

The hearth *A* is provided with a centrally disposed opening *D* within which extend portions of one or more electro magnets or inductors *E*, preferably of the form and arrangement illustrated. The electro magnet *E* is provided with windings *F* which receive current from a suitable source, the electro-magnet and winding being of the usual type employed in the art for producing the Joule effect.

Inasmuch as the intensity of the Joule effect is inversely proportional to the cross section of the molten mass, it will be seen that the portions of the metal within the inclined conduits or flues *C*, and in the shallow portions of the channels 1, 2, 3, etc., will be heated more rapidly than the metal in the deep portion of these channels, and consequently there will be a continuous upward movement of the molten mass within the inclined conduits or flues *C*, resulting in a continuous circulation of the molten mass through the channels and conduits, thereby effecting a thorough mixing of the molten particles and constantly renewing their contacting surface with the reactive agents.

While I have illustrated my invention in connection with three embodiments only thereof, it is to be understood that such embodiments may be modified within the scope of the appended claims without departing from the spirit of my invention.

Having now fully described my invention, I claim:

1. In a furnace of the type set forth, a hearth provided with a plurality of receptacles for molten metal, each having a longitudinally inclined bottom, laterally closed conduits connecting said receptacles and electro-magnetic means adapted to set up an induced electric current in metal contained in said receptacles and conduits, substantially as and for the purpose specified.

2. In a furnace of the type set forth, a hearth provided with a plurality of receptacles for molten metal, united in an endless system of crucible laterally closed inclined

conduits and electro-magnetic means adapted to set up an induced electric current in metal contained in said receptacles and conduits.

5 3. In a furnace of the type set forth, a hearth provided with a plurality of receptacles for molten metal, each having a longitudinally inclined bottom, laterally closed inclined conduits connecting opposite ends of 10 said receptacles and uniting same in an endless system or crucible and electro-magnetic means adapted to set up an induced electric current in metal contained in said receptacles and conduits.

15 4. In a furnace of the type set forth, a hearth provided with a plurality of open channels of greater depth at one end than the other, a plurality of laterally closed inclined conduits connecting the shallow end of each 20 channel with the deep end of the adjacent

channel and electro-magnetic means adapted to set up an induced electric current in metal contained in said channels and conduits.

5. In a furnace of the type set forth a plurality of open channels each having a longitudinally inclined bottom, the shallow end of each channel being adjacent the deep end of the next succeeding channel, said channels being united in an endless system or crucible by laterally closed inclined conduits and 25 electro-magnetic means adapted to set up an induced electric current in metal contained in said channels and conduits. 30

In testimony whereof I have hereunto set my hand in presence of two witnesses.

GUSTAVE GIN.
